UNITED STATES PATENT OFFICE.

HENRY M. BREWSTER, OF SPRINGFIELD, MASSACHUSETTS.

DESIGN FOR A BASIN-COCK.

SPECIFICATION forming part of Design No. 28,234, dated February 1, 1898.

Application filed August 12, 1897. Serial No. 648,052. Term of patent 14 years.

To all whom it may concern:

Be it known that I, HENRY M. BREWSTER, a citizen of the United States of America, residing at Springfield, in the county of Hampden and State of Massachusetts, have invented and produced a new and original Design for Basin-Cocks, of which the following is a specification, reference being had to the drawing, consisting of one figure, which is a side elevation of a basin-cock embodying my design.

The leading feature of my design is embodied in that part of the basin-cock above the spout.

Referring to the drawing, A represents the base of the body B of the basin-cock, and at a point substantially midway between said

base and the top of said cock the spout E is located, which has a downwardly-curved end. The body B above said spout narrows down to a smaller diameter and is provided with 20 an ornamental beading, and surmounting the whole is a cap F, having a dome-shaped closed end, as shown, imparting to the body B of the cock an ornamental and finished appearance.

Having thus described my design, what I 25 claim is—

The design for a basin-cock, substantially as herein shown and described.

HENRY M. BREWSTER.
